TRAY

Chauncey E. Waltman, Chicago, Ill., assignor to Edwin H. Eichler, Dundee, Ill.

Application December 27, 1948, Serial No. 150,361

Term of patent 14 years

(Cl. D44—10)

To all whom it may concern:

Be it known that I, Chauncey E. Waltman, a citizen of the United States, residing at Chicago, in the county of Cook, State of Illinois, have invented a new, original, and ornamental Design for a Tray, of which the following is a specification, reference being had to the accompanying drawing, forming a part thereof:

Fig. 1 is a top plan view of a tray embodying my new design;

Fig. 2 is a side elevation thereof;

Fig. 3 is a bottom plan view thereof;

Figs. 4 and 5 are left and right end views, respectively, of the tray according to Figs. 1 to 3,

I claim:

The ornamental design for a tray, as shown.
CHAUNCEY E. WALTMAN.
